US00D723431S

(12) United States Design Patent
Noguchi et al.

(10) Patent No.: US D723,431 S
(45) Date of Patent:  Mar. 3, 2015

(54) MOTORCYCLE

(71) Applicants: Hirotoshi Noguchi, Shizuoka-ken (JP);
Satoshi Isokari, Shizuoka-ken (JP)

(72) Inventors: Hirotoshi Noguchi, Shizuoka-ken (JP);
Satoshi Isokari, Shizuoka-ken (JP)

(73) Assignee: Yamaha Hatsudoki Kabushiki Kaisha
(JP)

() Term: 14 Years

(21) Appl. No.: 29/496,175

(22) Filed: Jul. 10, 2014

(30) Foreign Application Priority Data

Jan. 10, 2014 (JP) 2014-000275
